OSCAR BENDER, OF POTSDAM, GERMANY.

PROCESS OF MANUFACTURING OXIDS OF NITROGEN.

1,011,014.

Specification of Letters Patent.

Patented Dec. 5, 1911

Application filed April 6, 1909. Serial No. 488,203.

To all whom it may concern:

Be it known that I, OSCAR BENDER, a citizen of the Kingdom of Prussia, residing at Potsdam, in the Kingdom of Prussia, 5 German Empire, have invented certain new and useful Improvements in Processes of Manufacturing Oxids of Nitrogen.

This invention relates to an improved process for manufacturing oxids of nitrogen, 10 by oxidizing atmospheric nitrogen at high temperatures produced by burning hydrogen or substantially gaseous or gasified liquid combustible material or fuel such as water gas, illuminating gas, natural gas, 15 methane or petroleum vapors in an atmosphere rich in oxygen.

By means of the present invention increased yields of oxids of nitrogen are obtained.

Comparative systematic experiments have shown that the oxidation of atmospheric nitrogen in a flame produced by burning combustible materials containing hydrogen depends not only on the temperature used 20 but also upon a number of other facts which considerably affect the result and which were hitherto unknown or the importance of which was not understood. First I have found that the yield in oxids of nitrogen 25 greatly depends upon the perfect mixing of the combustibles with the gaseous mixtures supplied for combustion, at the moment when the flame is formed. The theoretical reason for this is to be found in the fact that 30 the completion of the reaction between nitrogen and oxygen requires a measurable interval of time which is scarcely shorter than that which is at the disposal of the gases from the commencement of the flame 35 reaction to the end thereof. When a part of this time is taken up by the diffusion of the gases *inter se*, the remainder will be insufficient for establishing the theoretically 40 possible equilibrium between the oxid of nitrogen and the remaining constituent parts of the burning gases. The yield of 45 oxid of nitrogen will therefore approach more and more the theoretical yield, the more perfectly the time occupied by the 50 gases in flowing through the flame is utilized for forming the equilibrium at the given temperature between nitrogen, oxygen, carbon, or the remaining materials taking part 55 in the combustion. This fact had not been taken into account in the previously known processes of manufacturing oxids of nitro-

gen according to which the flame formed by burning combustible materials is supplied with the other components (air or mixtures of nitrogen and oxygen richer in 60 oxygen than air) by partially forcing them in from the side and partially by blowing them into the same, so that consequently the yields remained relatively moderate. According to the present invention the perfect 65 mixing of the combustible materials (which has been recognized as an important factor) with the air or with air and oxygen mixtures during the combustion is obtained in a specially effective manner by dividing the 70 flame into numerous small pointed flames, the mixing being effected at the commencement or first stage in the formation of the flame by supplying the required quantity of nitrogen and oxygen to each separate 75 pointed flame to such an extent that the perfect mixing is already completed during the commencement or first stage in the formation of the flame. Further it was found that in order to obtain the absolutely 80 necessary complete combustion of all the carbon in the combustible or fuel to form carbonic acid a considerable surplus of oxygen is necessary. It is undesirable to obtain this surplus of oxygen by increasing the 85 supply of atmospheric air owing to the large amount of nitrogen supplied at the same time which nitrogen is useless and unnecessarily absorbs heat. It is found however that the combustion of the finely divided fuel 90 is facilitated in air enriched with such a quantity of oxygen that the mixture contains 50 to 90 per cent. of oxygen and 50 to 10 per cent. of nitrogen. The quantity of this mixture is preferably such that the 95 products of combustion contain 10 to 50 per cent. of free oxygen per volume by the use of which temperatures of from 1600 to 2500° are obtained in the hottest portion or zone of the combustion-chamber. Under these 100 conditions a surprisingly large proportion of nitrogen will be oxidized in the flame. In order to protect the oxids from decomposition which could easily happen as is well known, the mixture produced by the 105 reaction and containing in addition to oxid of nitrogen carbonic acid, free oxygen, nitrogen, and the water formed by burning the hydrogen contained in the combustible or fuel, is cooled as quickly as possible to 110 temperatures below 100° C., say between 60 to 80° C., and the water condensed thereby is

removed at once without being allowed to return into the combustion chamber. This is done by means of cooling devices which are arranged immediately adjacent to the 5 reaction zone and which consist preferably of cooled tubes, pipes or the like which are so arranged that the water condensed on them is either run off to the outside or collects in a condensation vessel. As the combination of nitrogen oxide with oxygen can 10 only take place after the separation of the water of condensation, the latter is entirely free, or almost so, of nitric acid.

The whole process is carried out in a 15 furnace shown diagrammatically in the accompanying drawings.

Figure 1 is a vertical section thereof and Fig. 2 a horizontal section.

This furnace comprises a casing *a* lined 20 with fire resisting material. A grate or burner *b*, composed of communicating tubular grate-bars, is disposed horizontally across the lower part of the casing. Some one of said bars communicates with an inlet pipe through which fuel gas is introduced into all of the bars, and all of the bars are provided with numerous very small orifices through which the fuel passes. As 25 illustrated, small tubes *c* are mounted over the various orifices of the hollow grate-bars. By this means the combustion of the fuel is forced to take place at the top of said tubes, thus preventing overheating and consequent rapid wear of the grate-bars. Moreover, 30 the fuel in passing up the tubes *c* receive an advantageous preliminary heating preparatory to combustion. The mixture of air and oxygen flowing up through the pipe *g* and between the grate-bars meets the numerous finely divided jets of fuel gas from 35 the orifices of the grate-bars or from the tubes *c*, and thus immediately forms a very intimate mixture. In the group of flames thus formed above the grate, or burner, the 40 formation of oxid of nitrogen takes place. The cooling system *d* is arranged beyond the hottest range or zone past which system the reaction gases flow when leaving the furnace, being thus cooled and the condensed 45 water formed by the combustion is drained off from the condensation vessel or trap, *e*. The cooled and dry re-action gases are then 50 passed on by the pipe *f*, in order to be further treated so as to form nitric acid or the 55 salts thereof.

It is of course understood that the burner is not restricted to the form described, for in-

stance the numerous little tubes supplying the combustible or fuel need not be arranged on a hollow grate in the furnace, but may 60 terminate directly in the furnace and supply the air and oxygen mixture through apertures arranged at regular intervals between the pipes or tubes.

Surprisingly favorable results have been 65 obtained in actual work, by means of the above described arrangement namely by dividing a number of large flames into numerous small or pointed flames to which the quantities of nitrogen and oxygen required 70 for obtaining favorable equilibrium conditions are added and thoroughly mixed with the flame at the commencement or first stage in the formation of the same and further by employing an air and oxygen mixture 75 containing 50 to 90 per cent. of oxygen in such quantities that the re-action gases contain from 10 to 50 per cent. of free oxygen and that by means of an immediate cooling of the re-action gases by cooled pipes 80 or the like, the water of condensation formed is drained off. The yield of oxids of nitrogen is increased tenfold or more as compared with that obtained when employing known processes. 85

I claim—

1. The process herein described of producing oxids of nitrogen, which consists in burning combustibles containing hydrogen in a furnace in the form of numerous small 90 pointed flames, supporting the combustion of said flames with a mixture consisting of nitrogen and 50 to 90% of free oxygen, and condensing the aqueous vapor thus formed.

2. The process herein described of producing oxids of nitrogen, which consists in burning a fuel-gas containing hydrogen in the form of numerous small pointed flames by passing said fuel-gas through very small orifices, supporting the combustion by a 100 mixture of air and oxygen containing 50 to 90% of oxygen in such proportion that the resulting reaction-gases contain 10 to 50% of free oxygen, and cooling the reaction gases to a temperature below 100° C., thus 105 condensing the water formed by the combustion.

In testimony, that I claim the foregoing as my invention, I have signed my name in presence of two subscribing witnesses.

OSCAR BENDER.
